UNITED STATES PATENT OFFICE.

HERMAN EDGAR SAMUEL CHAYES, OF NEW YORK, N. Y.

DENTAL BRIDGEWORK.

1,366,058.

Specification of Letters Patent.

Patented Jan. 18, 1921.

Continuation of application Serial No. 45,749, filed August 16, 1915. This application filed June 2, 1920.
Serial No. 385,999.

To all whom it may concern:

Be it known that I, HERMAN EDGAR SAMUEL CHAYES, a citizen of the United States, residing at New York, in the county of New York and State of New York, have invented certain new and useful Improvements in Dental Bridgework, of which the following is a specification.

This is a continuation of my former application Serial No. 45,749 filed August 16th, 1915, and it is intended to secure in this application the benefit of the filing date of my said former application so far as concerns the subject-matter disclosed in common in both applications.

The present invention relates to improvements in removable dental bridge-work, and has for one of its objects to provide a connection between the bridge and its piers by virtue of which the bridge-work is capable of slight movement vertically, as well as cross-wise of the dental arch, under masticating stress.

Another object is to provide such a connection which will be well within the skill and facilities of the average operator to construct, and the essential parts of which may be manufactured in quantity and of uniform size, so that interchange of parts and repair may be readily and conveniently effected.

Another object of the invention is to provide such a connection between the pin teeth and the dental arch which when in its completely assembled relation forms an active part of the occlusal surface.

Other objects and aims of the invention, more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claims.

In the accompanying drawings which are to be taken as part of this specification, and in which I have shown merely a preferred form of embodiment of the invention, Figure 1 is a perspective view illustrating a removable bridge embodying my invention as it appears when connected to its piers; Fig.

2 is an enlarged perspective of the removable bridge removed from the piers; Fig.

3 is a view similar to Fig. 1, but with the bridge removed; Fig. 4 is a detail view illustrating the relation of the connecting member to the socket member in the pier tooth; Fig. 5 is a cross sectional view taken on line 5-5 of Fig. 6 and Fig. 6 is a transverse sectional view through the assembled connection.

Referring to the numerals on the drawing, 5 indicates a first bicuspid and 6 a second molar, which, for illustration, are shown as piers for the support of the bridge shown in Fig. 2, this bridge including an artificially supplanted second bicuspid 7 and first molar 8. Each pier-tooth, 5-6, is provided with a socket portion 9, oblong in horizontal section, and extending transversely of the dental arch of which the pier tooth forms a part. Each socket portion 9 has a closed bottom wall 9², located toward the cervical portion of the tooth, opposed front and back walls 9¹, one toward the front and the other toward the back of the dental arch, an inside wall 9⁴, and an opposed outside wall (proximal to the edentate space) provided with a slot 9³. For reasons hereinafter explained, the front and back walls 9¹ are straight, as is also the bottom wall 9² of the socket, and it is preferred that the distance between the front and back walls 9¹ shall be greater than the distance between the inside and outside walls 9³-9⁴.

As will be noted in the drawings each of the sockets 9 extends to and terminates, as to its open end, at the occlusal surface of the pier teeth. The sockets thus described may be formed in inlays 12 made for the natural teeth (if natural teeth are being used as piers or abutments); or in case the crowns of natural teeth have been excised and artificial crowns substituted, the sockets are formed in the artificial crown or in a metallic portion thereof. Where the pier is a natural tooth, and the socket is formed in an inlay inserted in a recess or cavity of the tooth, it is evident that undesirable cutting of tooth structure is minimized by having the socket member of the oblong form shown, with its relatively wide side walls extending transversely of the dental arch, and located at and in the side of the tooth, that is, proximally with respect to the edentate space.

For practical reasons it is desirable to manufacture socket members separably and

of standard sizes, and solder them in place in inlays of natural teeth or metallic portions of artificial crowns, flowing metal over the outer surface as required to approximate the contour of the original complete tooth, and so that the pier presents the appearance indicated in Fig. 3.

The bridge which is to be supported by the piers 5 and 6 is shown best in Fig. 2, 10 and may comprise a saddle 10 of platinized gold or the like, carrying artificial teeth 7 and 8, with connecting members 11 connected respectively to the outer surfaces of the artificial teeth, for engagement in the sockets 9. Each connecting member 11 is in the 15 form of a T, and may conveniently be made of any suitable metal of a non-corrosive nature, the head of the T being of a size so that it will snugly fit down into the open end of 20 socket 9, and the stem of the T passing loosely into the slot 9³ of the outside socket wall. The ends of the stems of the T, indicated at 11', are secured in the outer side surfaces of the artificial teeth, preferably by 25 soldering in metallic inlays inserted in the artificial teeth. Thus we have a T-socket in and at the side of the pier, with the cross-bar of the T extending transversely of the dental arch, and a corresponding T-head 30 connecting member to engage in the socket. The slot 9³ is some wider than the thickness of the T-stem 11' of the male connecting member, and before the work is completed the side and bottom edges of the T-head of 35 the connecting member are given a slight curve as shown in Fig. 4, so that the T-head may have a rocking movement within the T-socket, transversely of the dental arch. The amount of this curvature is determined 40 by the operator in each case to accord so far as possible with the amount of soft tissue displacement which occurs during mastication. The T-heads will come to the dentist with the bottom and side edges straight, and 45 may readily be given a curvature as shown by grinding. The effect of this capacity for movement of the bridge transversely of the dental arch is to prevent the usual deleterious effect of communicable stress upon the 50 fixed piers or abutments. At the same time the bridge is free to move vertically of the dental arch, pressing upon and being pressed away by the gum tissue during mastication, thereby stimulating the circulation of blood 55 in the tissue in a natural manner. And by reason of the snug interfit between the T-head and the socket and the large areas of the side walls of the socket and of the T-head parts opposed thereto the parts will 60 normally be firmly held together, though deliberate separation may be readily accomplished. The dentist will also grind the outer edge of the T-head, that is, the edge which is exposed through the open end of 65 the socket so that when the bridge is in as-

sembled position within the mouth the exposed edge of the T conforms to the occlusal surface of the tooth carrying the socket.

Obviously somewhat the same results would be accomplished if the front and back 70 and bottom walls of the socket were convexed and the contacting edges of the T-head straight, the essential features being the provision of a socket and a connecting member 75 rockingly supported within, and upon the bottom wall of, the socket, so as to move transversely of the dental arch. And of course the socket member might be in the bridge, and the connecting member on the pier. 80

I claim:—

1. In a device of the kind described, a pier and a bridge part separably secured together for relative vertical movement, including an oblong closed-bottomed T-socket in one part 85 with wide side walls and narrow front and back walls, one of the side walls provided with a slot opening from the top and extending toward the bottom of the socket, the side walls disposed in planes transverse of the 90 dental arch in which the pier and bridge are included, and a T-head connecting member on the other part engaging the T-socket having a stem passing through the slot and a cross bar or head shaped to correspond to 95 and fitting the socket, with the side and inner edges of the head curved to make rocking contact with the front and back and bottom walls of the socket, respectively.

2. In a device of the kind described, a pier 100 and a bridge part separably secured together for relative vertical movement, including a closed-bottomed socket formed in the side of and opening occlusally from one part, and a connecting member on the side 105 of the other part fitting the socket and having curved surfaces rocking upon the bottom of the socket transversely of the dental arch in which the pier and bridge are included, the connecting member having also surfaces 110 exposed at the open end of the socket and forming a part of the occlusal surface of the member in which the socket is located.

3. In a device of the kind described, a pier and a bridge part separably secured 115 together for relative vertical movement, including an oblong closed-bottomed T-socket formed in the side and opening from the occlusal or incisive end of one part, with wide side walls and narrow front and back 120 walls, one of the side walls provided with a slot opening from the top and extending toward the bottom of the socket, the side walls disposed in planes transversely to the dental arch in which the pier and bridge 125 are included, and a T-head connecting member on the side of the other part engaging the T-socket and having a stem passing through the slot, and a cross bar or head shaped to correspond to and fitting 130

the socket, with its side and inner edges curved to make rocking contact with the front and back and bottom walls of the socket respectively, and with its outer edge exposed at the open end of the socket and forming a part of the occlusal surface of the member in which the socket is located.

4. In a device of the kind described, a pier and a bridge part separably secured together for relative vertical movement, the pier having the general overall contour of the original complete tooth, and consisting, as to that proximal portion thereof which faces the edentate space, of a metallic part having an oblong closed-bottomed socket therein, the bottom of the socket located toward the cervical portion of the pier and the socket having an open end at the occlusal surface of the pier and having wide side walls and narrow front and back walls, the proximal side wall having a slot extending from the open end of the socket toward the bottom thereof, the side-walls disposed in planes transverse of the dental arch, and a T-head connecting member on the bridge engaging the socket and having a stem passing freely through the slot and disposed in the line of the dental arch, and a head shaped to correspond to and fitting the socket, with the side and bottom edges of the head making contact with the front and back and bottom walls of the socket respectively, and with the outer edge of the head exposed at the open end of the socket and terminating at and completing the proximo-occlusal surface of the pier, the side and inner edges of the head being curved, so that they may rock on the front and back and bottom walls of the socket.

5. In a device of the kind described, a pier and a bridge part separably secured together for relative vertical movement, the pier having the general overall contour of the original complete tooth, and consisting, as to that proximal portion thereof which faces the edentate space, of a metallic part having an oblong closed-bottomed socket therein, the bottom of the socket located toward the cervical portion of the pier and the socket having an open end at the occlusal surface of the pier and having wide side walls and narrow front and back walls, the proximal side wall having a slot extending from the open end of the socket toward the bottom thereof, the side-walls disposed in planes transverse of the dental arch, and a T-head connecting member on the bridge engaging the socket and having a stem passing freely through the slot and disposed in the line of the dental arch, and a head shaped to correspond to and fitting the socket with the side and inner edges of the head making contact with the front and back and bottom walls of the socket respectively, and with the outer edge of the head exposed at the open end of the socket and terminating at and completing the proximo-occlusal surface of the pier.

6. In a device of the kind described, a pier part and a bridge part separably secured together for relative vertical movement, one of said parts having a closed-bottomed socket formed within its side portion and opening toward the occlusal end of the part, the occlusal surface of the socket-carrying part being interrupted and incomplete as to the proximal portion thereof in which the socket is located, and a connecting member attached to and projecting from the side of the other part and fitting the socket, the socket having wide side walls and narrow front and back walls, the side walls disposed in planes that are transverse to the dental arch in which the pier and bridge are included, and the connecting member having a head shaped to correspond to and fitting the socket, the inner portion of the head contacting with the bottom of the socket and the outer portion of the head provided with an occlusal surface which when the head is inserted in the socket, completes the occlusal surface of the socket-carrying part.

7. In a device of the kind described, a pier part and a bridge part separably secured together for relative vertical movement, one of said parts having a closed-bottomed socket formed within its side portion and opening toward the occlusal end of the part, the occlusal surface of the socket-carrying part being interrupted and incomplete as to the proximal portion thereof in which the socket is located, and a connecting member attached to and projecting from the side of the other part and fitting the socket, the socket having wide side walls and narrow front and back walls, the side walls disposed in planes that are transverse to the dental arch in which the pier and bridge are included, and the connecting member having a head shaped to correspond to and fitting the socket, the inner portion of the head contacting with the bottom of the socket and the outer portion of the head provided with an occlusal surface which when the head is inserted in the socket, completes the occlusal surface of the socket-carrying part.

8. In a device of the kind described, a pier part and a bridge part separably secured together for relative vertical movement, one of said parts having a closed-bottomed socket formed within its side portion and opening toward the occlusal end of the part, the occlusal surface of the socket-carrying part being interrupted and incomplete as to the proximal portion thereof in which the socket is located, and a connecting member attached to and projecting from the side of the other part and fitting the socket, the socket having wide side walls and narrow front and back walls, the side walls disposed in planes that are transverse to the dental arch in which the pier and bridge are included, and the connecting member having a head shaped to correspond to and fitting the socket, the inner portion of the head contacting with the bottom of the socket and the outer portion of the head provided with an occlusal surface which when the head is inserted in the socket, completes the occlusal surface of the socket-carrying part.

In testimony whereof I affix my signature.

HERMAN EDGAR SAMUEL CHAYES.
